UNITED STATES PATENT OFFICE.

JULIAN F. DENISON AND HARRY F. HOBSON, OF NEW HAVEN, CONNECTICUT; SAID DENISON ASSIGNOR TO SAID HOBSON.

MEANS FOR PUMPING LIQUID FUELS.

Application filed February 16, 1927. Serial No. 168,626.

Our invention relates to a fuel feeding system, and more especially to one suitable for use in feeding fuel to the burner of a heating system.

6 Three types of fuel feeding devices are commonly used in heating systems; one having a pump for feeding oil under high pressure, which is sprayed into the burner, entraining sufficient air as it passes in to form 10 a combustible mixture; a second in which an air pump forces a blast of air over an oil nozzle to entrain sufficient oil to form the combustible mixture; and a third in which both air and oil are forced in under pressure. The third system is generally considered to be the most efficient and in these 15 systems an oil pump of the geared piston type is commonly used for the fuel oil, while a rotary fan blower furnishes a supply of 20 air. A single motor is generally used to operate both the oil pump and the air blower, entailing the use of a complicated transmission, and also the fan blower must be provided with a lubricating system. As 25 one of the main objects of our invention we contemplate a system in which a single pump may be used to pump both air and oil, thus eliminating the transmission ordinarily necessary, and since oil is continually passing 30 through the pump no special oiling means has to be provided.

There is considerable danger from fire in oil heating systems, owing to the liability of oil to accumulate in the fire box and on 35 the basement floor when the burner is out by siphoning from the main supply tank and flow from the auxiliary tank in the basement, as well as from the associated mechanism. Elaborate means are usually provided 40 to prevent this flow of oil. As a further object of our invention we contemplate a system in which there is no tendency of the oil to flow when the burner is out and no special means is necessary to prevent siphoning.

45 A still further object of our invention is to provide a system having no open connections or vents within the building in which the device is located.

50 Another object of our invention is to provide an improved means for controlling the flow of oil in the system.

An additional object of our invention is to bring the air and oil into intimate contact before they are introduced into the car-

bureter or mixing device, in order that the 55 air may be saturated with oil vapors.

To these and other ends, our invention 60 consists in the novel features and combinations of parts to be hereinafter described and claimed.

In the drawings,

Fig. 1 is a general view of our improved fuel feeding system;

Fig. 2 is an enlarged view, shown in section, of a float and associated mechanism for 65 controlling the flow of oil in the system; and

Fig. 3 is an enlarged view of a nozzle for spraying the air and oil into the burner.

Referring to the drawings in which we have illustrated our invention by showing a 70 preferred embodiment thereof, the reference numeral 3 indicates in general a tank, composed of an upstanding tubular body 4, adjustably supported on a base 5, and caps 6 and 7. On the upper end of the tank 3 and supported by the cap 7, is a horizontal platform 8, having on one end a pump 9, which may be of any well known type, herein shown as a rotary pump, having a substantially cylindrical casing 10, an eccentric rotor 11, 75 mounted within the casing and in contact with the wall thereof between the inlet and outlet openings, and blades 12 held against the walls of the casing by centrifugal force, springs, or any other suitable means. As 80 shown in the drawings, one end cover of the pump is removed to show the interior arrangement. The outlet 13 of the pump 9 is connected to the tank 3 by the pipe 14, secured in the cap 7. A pipe 15 is connected 85 to the intake 16 of the pump 9, and by means of a T-fitting 17 is connected to a pipe 18 which leads to a supply tank 60 for liquid fuel. Connected to the other opening of the T-fitting 17 is an air pipe 19, which preferably leads to the outside of the building, and to an elevated position. Connected to the bottom of the tank 3 is an oil discharge line 20, having an upstanding portion 21 and a horizontal portion 22, while at the upper 90 end of the tank 3 is an air discharge pipe 23 connected by a pipe 24 to a nozzle 25 to which the oil supply pipe 22 is also connected. On or near the nozzle is a valve 26 for controlling the flow of oil through the 95 nozzle, while a valve 27 controls the flow of air through the pipe 24. Connected to the pipe 23 is an upstanding pipe 28, having at

its upper end a pressure relief valve 29, which may be of any well known type, not shown herein in detail. The exhaust opening of the pressure relief valve is connected 5 by a pipe 30 to the pipe 19. Inside the tank 3 is a vertically movable float 31, having a rod 32 secured thereto and extending upwardly therefrom and received within a pipe 33. Mounted on the pipe 33 is a check valve 10 34 having the customary ball valve 35, held to seat by the spring 36. From the check valve 34 a pipe 37 extends upwardly and is connected to the pipe 18 by the T-fitting 38.

On the outside of the tubular member 4 is 15 provided an oil level indicating gauge 39, which may be of any well known type. In the air line 15 a valve 40 is provided for controlling the amount of air passing to the pump 9, and in the oil line 18 a similar valve 20 41 is provided for regulating the amount of oil flowing to the pump. Gauges 42, 43 and 44 are provided in lines 28, 18 and 15, respectively, to indicate the pressure conditions in these lines. Mounted on the plat- 25 form 8 at the opposite end from pump 9 is an electric motor 45 connected to the pump 9 by means of a belt 46 and receiving power through wires 47, which are in series, with a thermostatically operated switch 48, which 30 may be of any desirable type, not shown in detail herein.

The nozzle 25 may be of any desirable type and herein is shown as consisting of a tubular body portion 51 having one end secured 35 in a T-fitting 52. A plug 53 is secured in the T-fitting opposite the member 51 and in the plug is mounted an oil pipe 54 connected to the pipe 22 by a union 55. The air pipe 24 is connected to the remaining opening in 40 the fitting. In the opposite end of the member 51 from the T-fitting is an oil nozzle 56, which is at one end connected to the pipe 54 and at the other end has an extension 57. Secured on the tubular member 51 at the 45 same end as oil nozzle 56 is a thimble 58, having a hole in its end surrounding the member 57 and providing therewith an annular opening for the passage of air, notches 59 being provided in the member 56 so that 50 air may pass therethrough.

A strainer 49 is provided in the line 15 to prevent the introduction of foreign matter into the pump 9 and also assists in bringing the oil and air into close contact. The 55 strainer may be of any well known type and is not shown herein in detail.

The adjustable base 5 of the tank 3 is made in two parts, as shown, which are secured together and clamped on tube 4 by 60 means of bolts 50. Suitable provision is made in the base 5 for clearing the oil level indicating glass 39 upon the base being adjusted to a higher position on the tank 3 than that shown in the drawings.

65 In operation, assuming the temperature in

the rooms of the house to be low enough so that the thermostat 48 closes the switch in the line 47, the electric motor being supplied with power drives the pump 9 which, through the suction created in the line 15, 70 draws in oil from the line 18 and air from the line 19, in proper proportions, through the regulation of valves 40 and 41. The air being brought into intimate contact with the oil becomes saturated with oil vapors and 75 both air and oil pass out of the discharge line 14 of the pump 9 to the tank 3 where they separate, the oil falling to the bottom of the tank and the air collecting at the top of the tank under pressure. The air pressure in the tank 3 forces the oil out through the lines 20, 21 and 22 to the nozzle 25, where it passes into the burner. At the same time compressed air from the tank 3 passes through the pipes 23 and 24 to the 85 nozzle 25 where it mingles with the oil being sprayed into the burner to form a combustible mixture.

As the pump continues to feed oil into the tank 3, the level in the tank 3 rises, carrying the float 31 with it to the point where the rod 32 unseats the valve 35 permitting air to pass from the tank 3 through the pipes 33 and 37 to the oil line 18. The introduction of air under pressure to the oil line 18 90 breaks the vacuum produced in this line by the pump 9 and stops the further flow of oil to the pump. Air now passes from line 18 and is fed to the tank 3. When the liquid level in the tank 3 falls to its normal 95 height the float 31 drops and the valve 35 becomes seated so that oil again flows to the pump 9.

The normal pressure that we have found desirable for use in our system is four 100 pounds. When the pressure in tank 3 increases beyond this point, the pressure relief valve 29 being in communication with tank 3, through pipes 23 and 28, opens, allowing the excessive pressure to pass off through 105 pipes 30 and 19 to the outside of the building, it being undesirable that this air should 110 be exhausted within the building, due to the oil vapors carried thereby.

By providing an upstanding portion in 115 the oil discharge line 20 and the horizontal portion 22 above the normal level of the oil in the tank 3 we are able to overcome any possibility of the oil passing from tank 3 into the burner after the motor has stopped. 120 When the motor stops and with it the pump 9, the air in tank 3 escapes by way of nozzle 25 and the pressure within the tank is reduced to atmospheric pressure, whereupon any oil in the nozzle and pipe 22 will flow 125 back to tank 3, thus preventing any dripping of oil into the furnace from nozzle 25. Although the pipe 22 and nozzle 25 are shown at a considerable distance above the base- 130 ment floor it will be readily understood that

the tank 3 may be disposed, for the greater part, below the level of the basement floor in a pit and the base 5 is made adjustable for this purpose being secured on the tank in 5 any desired position by the bolts provided.

It will be noted that the air pipe 19 by its connection with the oil pipe 18 provides a vent for the latter when the pump is not operated. This vent by introducing air into 10 the oil line effectively prevents any siphoning of oil into the system, it being understood that the pipe 18 is positioned above the level of oil in the main supply tank.

There being no open connections or vents 15 in our system within the building in which it is placed there is very little likelihood of any leakage and no danger from fire or explosions.

While we have shown and described some 20 embodiments of our invention, it will be understood that it is not to be limited to all the details shown, but is capable of modification and variation within the spirit of the invention and within the scope of the appended claims.

What we claim is:—

1. In a fuel feeding system, a main supply tank for liquid fuel, an auxiliary tank, a combined air and liquid fuel pump, a connection 30 between the outlet of said pump and said auxiliary tank, a connection between the inlet of said pump and said main tank, said last named connection permitting the free flow of liquid fuel from said tank to said 35 pump at all times, and a permanently open air inlet in said last named connection, said air inlet being at the highest point of said connection.

2. In a fuel feeding system, a main supply tank for liquid fuel, an auxiliary tank, a combined air and liquid fuel pump, a connection 40 between the outlet of said pump and said auxiliary tank, a connection between the inlet of said pump and said main tank, said last named connection permitting the flow of liquid fuel from said main tank to the pump at all times, a permanently open air inlet in said last named connection, and means for interrupting the flow of oil 45 through the connection to the main tank when the liquid level in the auxiliary tank reaches a predetermined height.

3. In a fuel feeding system, a main sup-

ply tank for liquid fuel, an auxiliary tank, a combined air and liquid fuel pump, a connection 55 between the outlet of said pump and said auxiliary tank, a connection between the inlet of said pump and said main tank, said last named connection permitting the flow of liquid fuel from said main tank to the pump at all times, a permanently open air inlet in 60 said last named connection, and means for interrupting the flow of oil through the connection to the main tank when the liquid level in the auxiliary tank reaches a predetermined height, said means for controlling the flow of oil through the connection between the main tank and the pump comprising a connection between the upper part of the auxiliary tank and the connection between the inlet of the pump and the main supply tank, a valve in said connection with the top of the auxiliary tank, and a float for unseating said valve when the oil level in 65 the auxiliary tank reaches a predetermined 70 level.

4. In a fuel feeding system, a main supply tank for liquid fuel, an auxiliary tank, a combined air and liquid fuel pump, a connection 75 between the outlet of said pump and said auxiliary tank, a connection between the inlet of said pump and said main tank, a permanently open air inlet in 80 said last named connection, a connection between the top of said auxiliary tank and the connection between the inlet of the pump and the main tank, and float controlled means for permitting the passage of air from the auxiliary tank through the connection between the top of the tank and the connection between the pump and main supply tank when the liquid fuel level in the auxiliary tank reaches a predetermined level, said float controlled 85 means including a valve in the connection with the top of the auxiliary tank and a float in the auxiliary tank, said float having a cross-sectional area but slightly less than the cross-sectional area of the interior of the tank whereby the float is sensitive to slight changes in the amount of liquid fuel contained in the tank.

In witness whereof, we have hereunto set our hands this 14th day of February, 1927.

JULIAN F. DENISON.
HARRY F. HOBSON.
